(57) **CLAIM**

The ornamental design for a collapsible table as shown and described.

DESCRIPTION

FIG. 1 is a front, left side, top perspective view of a collapsible table in a folded state showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front, right side, bottom perspective view thereof;

FIG. 9 is a rear, left side, bottom perspective view thereof, wherein legs are rotated downward in an unfolded state;

FIG. 10 is a front, left side, top perspective view thereof, wherein a circular base is extended downward in an unfolded state; and,

FIG. 11 is a front, left side, top perspective view thereof, wherein the legs are rotated downward in an unfolded state, the circular base is removed out as a chair, and a curve hanger and a rod are removed from a bottom surface of the collapsible table and disposed on a top surface of the collapsible table.

The broken lines in the drawings depict portions of the collapsible table that form no part of the claimed design.
